CLASP KNIFE

Emile H. Talmon, Scarsdale, N. Y., and Maurice S. Share,
Providence, R. I., assignors to Imperial Knife Company,
Inc., Providence, R. I., a corporation of Rhode Island

Application June 24, 1954, Serial No. 31,145

Term of patent 14 years

(Cl. D22—3)

Fig. 1 is a side view of a clasp knife showing our new design;

Fig. 2 is a top view thereof;

Fig. 3 is a bottom view thereof;

Fig. 4 is an end view as seen from the left of Fig. 1; and

Fig. 5 is an end view as seen from the right of Fig. 1.

We claim:

The ornamental design for a clasp knife, substantially as shown.
